UNITED STATES PATENT OFFICE

124,209

DESIGN FOR A PLATE OR SIMILAR ARTICLE

James M. Smith, Jr., New Castle, Pa., assignor to
Shenango Pottery Company, New Castle, Pa.,
a corporation of Pennsylvania

Application June 3, 1940, Serial No. 92,792

Term of patent 14 years

To all whom it may concern:

Be it known that I, James M. Smith, Jr., a citizen of the United States, residing at New Castle, Pennsylvania, have invented a new, original, and ornamental Design for a Plate or Similar Article, of which the following is a specification, reference being had to the accompanying drawing, forming part thereof. In the drawing:

Fig. 1 is a top plan view of a plate showing my new design; and

Fig. 2 is a sectional view along the line II-II of Fig. 1.

The dominant feature of the design is the surface ornamentation appearing on the article, and while shown applied to a plate, said ornamentation is intended to be applied to other similar articles.

I claim:

The ornamental design for a plate or similar article, substantially as shown and described.

JAMES M. SMITH, JR.
